UNITED STATES PATENT OFFICE.

EDWIN R. LANGFORD, OF LOS ANGELES, CALIFORNIA, ASSIGNOR OF ONE-HALF TO JESSIE C. HEWITT, OF LOS ANGELES, CALIFORNIA.

ROCK-DRILL.

No. 796,228.

Specification of Letters Patent.

Patented Aug. 1, 1905.

Application filed December 7, 1903. Serial No. 184,140.

To all whom it may concern:

Be it known that I, EDWIN R. LANGFORD, a citizen of the United States, residing at Los Angeles, in the county of Los Angeles and State of California, have invented a new and useful Rock-Drill, of which the following is a specification.

This invention relates to a drill in which the power is derived from a mechanical source, but the working impulse of the drill given directly by compressed air.

The main object of the invention is to secure the advantages of an air-drill without the expense of installing the plant required for an air-drill—such as air-compressors, piping, &c.—and this object is attained by producing the compressed air within the machine itself.

Another object is to impel the drill by compressed air confined directly behind and in a straight line with the drill-carrying element, so that the striking of the drill against the rock is directly caused by the expansion of the air and indirectly by the mechanical operation of the parts of the drill. Thus all jar on the mechanism of the drill or prime actuating parts is eliminated.

Another object is to provide means for maintaining the supply of compressed air at a substantially uniform pressure.

Another object of the invention is to provide a rock-drill which is simple in construction, effective in operation, readily controlled, and durable.

Other objects and advantages of the present invention will appear from the following description.

The accompanying drawings illustrate the invention; and, referring to the same, Figure I is a vertical longitudinal section through the drill with the piston retracted. Fig. II is a plan view of the drill with the piston advanced. A portion of the cylinder is broken away to show the piston and rifle-bar, and the auxiliary air-pump is shown in horizontal section. Fig. III is a plan view of the auxiliary air-pump and adjacent portions of the drill. Fig. IV is a section on line IV IV, Fig. I, looking in the direction of the arrow. Fig. V is a view looking at the front toward the rear of the front end parts of the drill, the parts in the background being removed. Fig. VI is a vertical longitudinal section through the driving-shaft and clutch. Fig. VII is a

perspective detail of a sliding pawl of the clutch. Fig. VIII is a view looking toward the lower face of the upper member of the clutch. Fig. IX is a view looking toward the upper face of the lower member of the clutch. Fig. X is an end view of a valve in the air-pump, which controls the admission of air from the pump to the cylinder of the drill. Fig. XI is a perspective view of the relief-valve for the air-pump. Fig. XII is a cross-section on line XII XII of Fig. II.

1 designates a supporting-shell having ways 2, and 3 is the drill-cylinder, which is mounted on a shoe 4, which slides in the ways 2. Projecting from the lower part of the cylinder 3 is a nut 5, which engages a feed-screw 6, the latter being rotatably mounted in a head 7, which is attached to supporting-rods 8, projecting from the rear of the shell 1. A suitable crank 9 is provided on the end of the screw 6. Projecting from the forward end of the cylinder 3 is a tubular extension 10, the upper part of which is slotted, as at 11. The extension 10 takes into the forward end of the cylinder 3, fitting closely therein, and is provided with flanges 12, which abut against the front end of the cylinder. The inner end of the extension 10 thus forms a shoulder *h*. A sleeve 13 is slidably mounted within the extension 10 and is provided with a wing 14, which plays back and forth through the slot 11 when the drill is in operation, the wing 14 preventing the sleeve 13 from turning.

15 is a piston which is mounted on the piston-rod 16 and is provided with a nose 17, forming a shoulder *g*, and the nose 17 abuts against a shoulder 18, formed on the piston-rod, there being a pin 19, which fastens the piston in place on the piston-rod. The piston-rod 16 extends forward through the sleeve 13 and carries on its end a suitable chuck 20 for the attachment of the drill 21. The forward end of the sleeve 13 abuts against the chuck 20, and a collar *a*, which is pinned on the piston-rod, holds the sleeve 13 securely in place on the piston-rod. Attached to the rear end of the piston-rod is a rifle-bar 22, which plays through a rifled sleeve 23, which is rotatably mounted in a stationary block 24, the latter being rigidly fastened within the cylinder 3. The sleeve 23 is provided with a ratchet 25, and suitable dogs 26 prevent rearward movement of the ratchet and sleeve 23.

A head 27 is attached to the rear end of

the cylinder 3, being provided with a forward extension 28, which closely fits within the rear portion of the shell forming the cylinder. The head 27 is provided with a vertical journal-bearing 29, the upper part of which is enlarged to form a cup 30.

The driving-shaft comprises two sections, the upper section 31 of which is mounted in a journal-bearing 29, while the lower section 32 is connected to the upper section by a clutch 33, which may be of any construction which will allow the upper section of the shaft to rotate ahead of the lower section should occasion require.

34 designates a flexible shaft which is attached by a suitable coupling 35 with the lower section of the driving-shaft 32. The driving-shaft may be a continuous solid shaft, and the employment of the clutch 33 is not necessarily essential, as will be hereinafter pointed out.

As it may be desirable sometimes to employ a clutch such as mentioned, I have shown and illustrated one form, in which 36 designates the lower member which is rigidly mounted on the upper end of the lower section of the driving-shaft 32 and which also serves as a fly-wheel. The lower section of the clutch 36 is provided with pockets 37, which receive slideable dogs 38. The slideable dogs 38 have oppositely inclined faces, as shown, and the dogs are prevented from turning axially by means of splines 39, which take into suitable grooves formed in the lower part 36 of the clutch. Suitable springs 40 are employed for resiliently holding the dogs up.

41 designates the upper portion of the clutch, the lower face of which is contiguous to the upper face of the lower part 36 and is provided with a series of shallow pockets 42, preferably spaced equidistant in a circle, as shown, and are adapted to receive the upper ends of the dogs 38. The dogs 38 are limited in their upward movement by the tops of the splines 39 striking against the lower face of the upper part of the clutch 41, and the beveled faces of the dogs 38 permit of a rotation of the upper part 41 in one direction relative to the lower part 36, the dogs 38 yielding downwardly to allow this motion.

42 is a gear keyed to a stub-shaft 80, the shaft 80 being mounted in the journal-bearing 29, and a crank-pin 43 is screwed into the gear 42. A pitman 44 is connected with the gear 42 by the crank-pin 43 and with the sleeve 11 by a pin 45, which is screwed into the wing 14. A pinion *c* on the upper end of the shaft 31 meshes with the gear 42.

50 designates in a general way an auxiliary air-pump, which comprises a cylinder 51, which is attached to the side wall of the main cylinder 3. A trunk-piston 52 is provided which extends through the end of the cylinder 51, and a yoke 53 is fastened to the projecting end by nuts 54 and 55, which are

screwed onto the piston and clamp opposite sides of the yoke.

56 designates a yoke, the two legs of which are fastened to the wing 14 by cap-screws 57, and the yoke 56 is provided with an offset arm 58.

59 designates a pair of connecting-rods, which connect the arm 58 with the yoke 53, as shown.

The piston 52 has an internal bore of two diameters. The larger bore receives a longitudinally-corrugated valve 60, which is slideable in the piston 52, being resiliently pressed against a shoulder 61 by a coil-spring 62, the tension of which may be regulated by an adjusting-screw 63, which is screwed into the outer end of the piston 52. The adjusting-screw 63 is provided with a central hole 64 for the escape of air when the valve 60 is moved away from its seat.

The cylinder 51 is provided with a web 65, having a central air-passage 66, and the web forms a seat for an admission-valve 67, the periphery of which is corrugated, as shown in Fig. X, and is provided with a stem 68, which is slideable within the hollow shank of an adjusting-screw 69, which is screwed into the end of the cylinder 51. 70 is a coil-spring interposed between the valve 67 and the adjusting-screw 69 and serves to normally hold the valve 67 yielding against its seat, its tension being regulated by an adjusting-screw 69. The cylinder 51 is thus formed into two chambers, one of which may be termed the "piston-chamber" and the other the "valve-chamber." The valve-chamber has an outlet 71, which is connected by a pipe 72 with an inlet 73 in the main cylinder 3. While the piston 15 covers the inlet 73 when fully retracted and does not uncover the inlet 73 until it has moved forward to the position indicated by dotted lines in Fig. II, it is obvious that the pump 50 is compressing air during the outward stroke of the piston 15, and air from the pump cannot enter the cylinder 3 until it has been compressed sufficiently to overbalance the pressure in cylinder 3, and the inrush of compressed air from the pump 50 to the cylinder 3 does not occur until the piston 15 has substantially reached the outward limit of its stroke and the pressure within the cylinder 3 has fallen to practically its lowest point. Hence the location of the inlet 73 is not absolutely arbitrary, it of course being necessary that the inlet 73 be uncovered when the piston 15 has reached the limit of its outward stroke. The cylinder 51 is also provided with air-holes 74, which admit air to the cylinder when the piston 52 is retracted, but which are closed as soon as the piston moves forward.

Motion is imparted to the driving-shaft by the flexible shaft 34, thus rotating the pinion *c* and gear 42 and reciprocating the sleeve 11 through the medium of the pitman 44, when

the piston moves forward. When the piston retracts, it compresses the air back of it, so that as soon as the crank-pin 43 passes the dead-center this compressed air gives an impetus to the piston which drives it forward by the expansion of the compressed air back of the piston. As the piston moves forward it carries with it the sleeve 13 and pitman-rod 44, causing the pinion *c*, gear 42, and shaft 31 to be rotated ahead, and this forward movement of the parts may be a trifle faster than if moved directly by the flexible shaft 34. However, the flexible shaft 34 permits of this faster forward movement, and by the nature of its construction the flexible shaft follows up the rotative lead of the parts during the forward stroke, so that it is ready to return the piston at the termination of the forward stroke. Thus it will be seen that the working stroke of the piston and striking of the drill is performed directly by compressed air and that the return stroke of the piston and drill is caused directly by the mechanical operation of the parts. The drill strikes the rock from the impulse derived from the compressed air, and thus at the time of impact of the drill against the rock the force back of the piston is resilient and the cushioning effect of the compressed air obviates the dangerous shock of the reaction upon the machine, which would occur if the drill were propelled forward by the mechanical movement of the pitman and gear. As the sleeve 14 is reciprocated by the piston the piston 52 is reciprocated within its cylinder 51 through the medium of its connections before described, and at every forward stroke of the drill air is compressed within the cylinder 51. The tension of the spring 70 is regulated so that when the pressure within the main cylinder 3 falls below a certain point the valve 67 will be opened by the compressed air within cylinder 51, which will allow the air to pass through the pipe 72 into the cylinder 3, thus raising the pressure within the cylinder 3 to the required point. As soon as the pressure within the cylinder 3 has been raised to the required point it causes a balancing of pressures within the cylinders 51 and 3, which allows the spring 70 to close the valve 67, and it does not open again until the pressure within the cylinder 3 has again fallen below the desired point. Thus the pressure within the cylinder 3 is maintained automatically. When the pressure within the cylinder 51 rises above a desired point, the spring 62 yields and allows the valve 60 to be forced away from its seat, which allows the escape of air through the corrugations and through the air-passage 64, relieving the pressure within the cylinder 51 automatically. As soon as normal pressure has been restored within the cylinder 51 the valve 60 is closed by its spring 62.

The head 27 is provided with an air-cham-

ber *d*, in which the rifle-bar 22 lies when the piston is retracted, and the block 23 is provided with perforations *e*. It will be noted that the thickness of the sleeve 24 is such that when the piston is retracted there is a space between it and the front edges of the head 27, so that when the piston is retracted by the mechanism the air is compressed not only within the clearance-space between the piston and block 23, but also within the air-chamber *d*, inasmuch as the latter is in communication with the clearance-space behind the piston through the medium of the perforations *e*. This gives a sufficient volume of air to be compressed, so that in advancing the drill there will be a more steady pressure of air behind the piston than there would be if the piston pressed a very small volume into merely clearance-space. In the latter case the compression would be extremely high and the fall in pressure would be very great, which result is not desired. In the forward stroke of the piston as soon as the nose 17 enters the rear end of the extension 10 an annular pocket is formed between the shoulders *g* and *h*, which quickly grows smaller as the piston advances, compressing air therein, so that the piston at the limit of its forward stroke is cushioned. This air-cushion obviates shock to the mechanical parts which move the piston and is useful when the drill is running free from impact with the rock. It should be noted that no opposition is given to the forward stroke of the piston until the nose 17 enters the extension 10, as up to that time the air in front of the piston is free to escape into the extension 10 and out of the slot 11.

What I claim is—

1. A cylinder, a piston therein, a drill-carrying element connected to the piston, mechanism for retracting the piston and compressing air behind the piston, auxiliary means for furnishing compressed air behind the piston, and means for automatically relieving the pressure within the auxiliary means.

2. A cylinder, a piston therein, a piston-rod connected thereto, a pitman, means for connecting the pitman with the piston-rod, a head connected to the rear of the cylinder, the upper portion of which is cupped and a portion of the head being formed in a journal, a shaft in the journal, a gear on the shaft, said gear lying within the cupped portion, and a crank-pin connecting the pitman and gear.

3. A cylinder, a piston therein, a piston-rod connected thereto, a pitman, means for connecting the pitman with the piston-rod, a head connected to the rear of the cylinder, the upper portion of which is cupped and a portion of the head being formed in a journal, a shaft in the journal, a gear on the shaft, said gear lying within the cupped portion, a crank connecting the pitman and gear, another journal formed in the head, a driving-shaft mounted

in the journal, a pinion on the driving-shaft within the cupped portion of the head and meshing with the gear.

4. A cylinder, a piston therein, a piston-rod connected thereto, a slotted extension from the forward end of the cylinder, a sleeve on the piston-rod having a wing which plays in the slot of the extension, a head on the rear of the cylinder, the head having a cupped portion and a plurality of journals, a shaft in one journal, a gear on said shaft and within the cupped portion, a driving-shaft in the other journal, a pinion on said driving-shaft within the cupped portion meshing with the gear, a pitman, a crank-pin through one end of the pitman screwed to the gear, and a pin through the other end of the pitman screwed to the wing of the sleeve.

5. A cylinder, a piston therein, a piston-rod connected thereto, a pitman, means for connecting the pitman with the piston-rod, a gear connected to the pitman, an air-pump, means for admitting air from the air-pump to the cylinder, and means connecting the air-pump with the piston-rod for working the air-pump.

6. A cylinder, a piston therein, a piston-rod connected thereto, a pump-cylinder, a piston in the pump-cylinder, a yoke on the pump-piston, a yoke connected with the first piston-rod, rods connecting the two yokes, and means for conveying compressed air from the pump-cylinder to the first cylinder.

7. A cylinder, a piston therein, a piston-rod connected thereto, a sleeve on the piston-rod, a pitman connecting with the sleeve, means for actuating the pitman, a pump-cylinder attached to the first cylinder, a piston in the pump-cylinder, means for connecting the pump-piston with the first piston-rod, means for conveying compressed air from the pump-cylinder to the first cylinder, and a valve in the pump-cylinder for controlling the admission of compressed air to the first cylinder.

8. A cylinder, a piston therein, a piston-rod connected thereto, a sleeve on the piston-rod, a pitman connecting with the sleeve, means for actuating the pitman, a pump-cylinder attached to the first cylinder, a piston in the pump-cylinder, means for connecting the pump-piston with the first piston-rod, means for conveying compressed air from the pump-cylinder to the first cylinder, a valve in the pump-cylinder for controlling the admission of compressed air to the first cylinder, and a relief-valve in the pump-piston for preventing an abnormal pressure within the pump-cylinder.

9. A cylinder, a piston therein, a piston-rod connected thereto, a sleeve on the piston-rod, a pitman connecting with the sleeve, means for actuating the pitman, a pump-cylinder attached to the first cylinder, a piston in the pump-cylinder, means for connecting the pump-piston with the first piston-rod, means for conveying compressed air from the

pump-cylinder to the first cylinder, a valve in the pump-cylinder for controlling the admission of compressed air to the first cylinder, said admission-valve having a corrugated periphery, a web in the pump-cylinder forming a seat for said valve, a spring for pressing said valve against said web, and means for regulating the tension of said spring.

10. A cylinder, a piston therein, a piston-rod connected thereto, a sleeve on the piston-rod, a pitman connecting with the sleeve, means for actuating the pitman, a pump-cylinder attached to the first cylinder, a piston in the pump-cylinder, means for connecting the pump-piston with the first piston-rod, means for conveying compressed air from the pump-cylinder to the first cylinder, a valve in the pump-cylinder for controlling the admission of compressed air to the first cylinder, said admission-valve having a corrugated periphery, a web in the pump-cylinder forming a seat for said valve, a spring for pressing said valve against said web, means for regulating the tension of said spring, said pump-piston having a bore of two diameters, a valve having a corrugated surface lying within the larger bore, a spring for pressing said valve against its seat, and means for regulating the tension of said spring.

11. A cylinder, a piston therein, a piston-rod connected thereto, a pitman, means for connecting the pitman with the piston-rod, a gear connected to the pitman, means for driving the gear, a pump-cylinder attached to the first cylinder, said pump-cylinder having a web forming a valve-chamber and a piston-chamber in the pump-cylinder, a pipe communicating the valve-chamber with the first cylinder at a point behind the extreme retracted position of its contained piston, a valve for closing communication between the two chambers of the pump-cylinder, and adjustable resilient means for holding said valve against its seat.

12. A cylinder, a piston therein, a piston-rod connected thereto, a pitman, means for connecting the pitman with the piston-rod, a gear connected to the pitman, means for driving the gear, a pump-cylinder attached to the first cylinder, said pump-cylinder having a web forming a valve-chamber and a piston-chamber in the pump-cylinder, a pipe communicating the valve-chamber with the first cylinder at a point behind the extreme retracted position of its contained piston, a valve for closing communication between the two chambers of the pump-cylinder, adjustable resilient means for holding said valve against its seat, and adjustable means for relieving the pressure within the piston-chamber.

13. A cylinder, a piston therein, a piston-rod connected thereto, a pitman, means for connecting the pitman to the piston-rod, a head at the rear of the cylinder having two journals, a shaft in one journal, a gear on the

shaft connected to said pitman-rod, a driving-shaft mounted in the other journal, said driving-shaft being in two sections, a pinion attached to the upper section and meshing with said gear, and a clutch connecting the two sections of the driving-shaft comprising two members; spring-pressed pawls slidably mounted in pockets in one member, the other member of the clutch having a series of shallow pockets adapted to be engaged by said pawls, said pawls having inclined end faces whereby the two members of the clutch may have a differential movement.

14. A cylinder, a piston therein, a drill-carrying element connected to the piston, an air-chamber at the rear of the cylinder and a mechanism for retracting said piston to compress air behind the piston within the cylinder and also within said air-chamber.

15. A cylinder, a piston therein, an auxiliary air-chamber at the rear of the cylinder and communicating therewith, a drill-carrying element connected to the piston, and means for retracting said piston and compressing air within the cylinder at the rear of the piston and also within the auxiliary air-chamber, said piston being advanced by the compressed air so produced.

In testimony whereof I have hereunto signed my name, in the presence of two subscribing witnesses, at Los Angeles, in the county of Los Angeles and State of California, this 27th day of November, 1903.

EDWIN R. LANGFORD.
